UNITED STATES PATENT OFFICE.

JAMES WHITELAW, OF ST. LOUIS, MISSOURI, ASSIGNOR, BY MESNE ASSIGNMENTS, TO CHICAGO PNEUMATIC TOOL COMPANY, OF CHICAGO, ILLINOIS, A CORPORATION OF NEW JERSEY.

ENGINE.

1,143,563.

Specification of Letters Patent. Patented June 15, 1915.

Application filed December 27, 1898. Serial No. 700,432.

To all whom it may concern:

Be it known that I, JAMES WHITELAW, a citizen of the United States of America, residing at the city of St. Louis, in the State of Missouri, have invented a certain new and useful Improvement in Engines, of which the following is a description, reference being had to the accompanying drawings, forming part of this specification.

0 My invention has for its object the production of a small and compact high-speed engine of maximum power in proportion to its size and weight, and adapted more particularly for use as the engine or motor part 5 of light, portable, manually-handled rotary tools of various characters, such as drills, flue-cutters and rollers, and the like. Its novelty consists in the various features of construction, arrangement and combination 0 of parts by which this object is attained; also in novel and simple means for reversing the engine at will, and for changing the speed of the tool without changing the speed of the engine; all as hereinafter more fully 5 explained.

In the accompanying drawings my invention has been illustrated as embodied in a rotary drill, and in said drawings Figure 1 represents what may be termed a front elevation of the machine, with the lower part of the casing removed to expose the gearing through which the tool-shaft is driven from the engine-shaft; Fig. 1^a a longitudinal section through the left hand one of the two handles shown in Fig. 1, illustrating the throttle-valve for controlling the inlet of the motive fluid, and the reversing gear; Fig. 1^b a sectional detail on the line 1^b—1^b of Fig. 1, showing the reversing slide and the rack and gear for operating it in elevation; Fig. 2 a vertical section, partly in the plane indicated by the dotted line 2—2 on Fig. 1 and partly in the plane indicated by the dotted line x—x on Fig. 1, the former being a middle vertical section through the tool-shaft and three members of the train of gearing, and the latter a section through the axis of oscillation of the cylinders; Fig. 2^a a horizontal section approximately on the line 2^a—2^a of Fig. 1, with the rear portion of the gear casing broken away and the front portion in place; Fig. 3 an enlarged

detail front view of the machine, with the forward side of the casing and the parts carried by it removed, to expose the cylinders and crank-shaft within the casing; Fig. 4 a vertical section approximately on the line 4—4 of Fig. 3; Fig. 5 a corresponding view on the line 5—5 of Fig. 3.

The same letters-of-reference are used to indicate corresponding parts in all the views.

The cylinders and the engine-shaft or crank-shaft are inclosed within a casing A of suitable shape, while a supplemental casing A' partly shown in Fig. 2^a incloses the train of gearing at the bottom of the casing A. Journaled at its opposite ends in bearings in the casing A, Fig. 3, is a double crank-shaft B to whose cranks are connected the piston-rods C C' of a pair of oscillating engines D D' whose trunnions are journaled at their outer ends in bearings in the casing A and at their inner ends in bearings in a support E projecting upward or forward from the casing A between the two engines, Figs. 2, 4, and 5.

The crank-shaft B and the trunnions of the engines are journaled in ball-bearings, the balls being confined in cups or housings F screwed into the casing A and support E as shown in Figs. 2 and 3.

Steam is admitted to the engines through a tubular handle G, Fig. 1, which handle has connected to its left hand end a flexible hose H leading to the motive fluid supply. At 85 its right hand end the tubular handle G is screwed into a slide I confined in guideways upon the left hand side of the casing in Figs. 1 and 3 and adapted to be slid backwardly and forwardly therein. The 90 handle G and its connection with the slide I are shown in section in Figs. 1^a and 5. Formed integral with the slide I is an inwardly extending curved yoke J, which is hollow and whose internal passage forms a 95 continuation of the passage in the handle G, Fig. 5. This hollow yoke J extends over and around the middle support E between the two engines, and down between said engines at its opposite ends in position for 100 ports K K' formed in its opposite sides at its opposite ends to coöperate with ports L L' formed in the side walls of the engine cylinders at the opposite ends of the

latter. The adjacent surfaces of the engine cylinders and yoke J at the ports mentioned are properly shaped and finished to fit snugly together and form coöperating 5 valve faces.

Under this construction and arrangement of the parts the admission of motive fluid through the handle G and hollow yoke J will serve to drive the engines in the usual 10 manner. In Fig. 4 the engine D is taking motive fluid at its left hand end, while its right hand end is open to the exhaust, so that the engine shaft is being driven in the direction of the arrow. It will be observed, 15 however, that if the yoke J should be moved upward (in Fig. 4) until the ports K L were carried out of register and the ports K' L' brought into register and motive fluid thereby admitted to the port L' the piston 20 will be driven toward the left, instead of toward the right, and the direction of motion of the engine be reversed. This very simple method of reversing the engine is provided for by the adjustment of the slide 25 I in its guideways upon the casing A. As shown in the various views of the drawings the slide I is in what may be termed its rearward position, having reference to Figs. 1 and 3; but if it be slid forward (upward 30 in Figs. 4 and 5) the yoke J will be carried forward or upward, with the result of reversing the direction of motion of the engines, as will be readily understood. Any suitable means for shifting the slide I for 35 this purpose may be employed without departing from this feature of my invention. I have illustrated one convenient form of means, which may be described as follows, reference being had more particularly to 40 Figs. 1, 1^a and 1^b. As there shown the slide I is confined in place in its guideway in the casing A by two narrow metal strips or plates M, N whose edges overlap the opposite edges of the slide I and confine it in 45 place. The plate M has gear teeth a formed upon its inner edge, Fig. 1^b, while the plate N has two notches b formed in its inner edge. Mounted upon the tubular handle G 50 is a sleeve O which at its inner end abuts against the slide I and has formed upon its one side gear teeth a' meshing with the rack a, and on its opposite side two projecting teeth c at some distance apart, adapted to 55 coöperate with the notches b in the plate N. A coiled spring d surrounding the tubular handle G within the sleeve O and bearing at one end against an internal shoulder on said sleeve and at its opposite end against 60 a collar e fast upon the handle, Fig. 1^a, presses the sleeve O toward the right, but permits it to be slid to the left against the resistance of such spring, a flange upon the collar e limiting its movement in the latter 65 direction. When the gear teeth a' on the sleeve O are engaged with the rack a on the

plate M, and one of the teeth c on the opposite side of the sleeve engaged with one of the notches b in the plate N, the sleeve O will be locked from rotation, and the slide I likewise locked in fixed position in its 70 guideway. By sliding the sleeve O to the left to its limit of movement, however, its tooth c will be disengaged from the notch in the plate N, without disengaging its gear teeth a' from the rack of the plate M (owing 75 to the fact that the plate M and rack are considerably thicker than the plate N, as shown), and when so disengaged the sleeve O may be turned upon the tubular handle G. When so turned its gear a' will roll 80 along the rack a of the plate M and move the slide I along its guideway in the corresponding direction. Thus, in Fig. 1^b the turning of the sleeve O in the direction of the arrow will raise the slide I, and when it 85 has reached its limit of movement the lower tooth c on the sleeve O will be brought opposite the upper notch b in the plate M, and upon then releasing the sleeve O the coiled spring will force it to the right against the 90 slide I and engage said tooth and notch, and thereby lock the parts in such position. This shifting of the slide I will reverse the engine in the manner before explained.

The throttle-valve P for controlling the 95 supply of motive fluid is located in and upon the tubular handle G a short distance to the left of the sleeve O, so that the operator may at any time readily slip his left hand from one to the other, turning the throttle-valve to 100 cut off the motive fluid supply, then turning the sleeve O to reverse the engine, and then turning the throttle-valve back to admit the motive fluid. The throttle-valve P illustrated in the drawings is, in its general construction, of old and well-known form, and need not be described further than to say that by turning the outer sleeve of the valve to one position communication between the 105 passages entering the opposite ends of the 110 valve is cut off, and by turning the sleeve to its opposite position such communication is reestablished.

Secured to the opposite side of the casing A is another handle G', which in the present 115 instance is also hollow or tubular and constitutes one of the exhaust openings from the casing A.

Having now described the engine or motor proper of the machine, it remains to explain 120 the train of gearing by which its power is transmitted to the tool-shaft. As shown in Fig. 3, the engine-shaft B has secured upon its lower end, beneath the main casing A, a pinion Q, which pinion, as shown in Fig. 2^a, 125 meshes with a gear wheel R mounted on a stub-shaft or spindle S secured in and depending from one end of a lever T fulcrumed upon the bottom of the casing A at U. The gear R has fast upon its upper side a pinion 130

V which meshes with a gear W fast upon the tool-shaft X, Figs. 2 and 2^a, which shaft has its bearing and support in a long sleeve Y secured at its lower end to the outer or forward end of an arm Z pivoted to the top of the casing A at Z'.

It results from the foregoing train of speed-reducing gearing between the engine-shaft B and the tool-shaft X that the latter will be driven at a correspondingly reduced rate of speed and proportionately greater power, as compared with the engine-shaft. If, however, it be desired to drive the tool-shaft at a higher speed relatively to the speed of the engine-shaft the front ends of the lever T and arm Z, and connecting sleeve Y, may be swung to the right from the position shown in Figs. 1 and 2^a, and the gear R disengaged from the pinion Q and the gear W engaged directly with said pinion Q, and thereby correspondingly increasing the rate of speed of the tool-shaft. For the purpose of holding the parts in these opposite positions of adjustment, with the pinion Q of the engine-shaft meshing either with the gear R or directly with the gear W on the tool-shaft, there is provided upon the top of the supplemental casing A' which incloses the gearing, Fig. 2^a, a spring-pressed latch-pin B' adapted to coöperate at its inner end with two holes in the forward end of the lever T or sleeve Y. When the parts are in left hand position, Fig. 2^a, this latch-pin will be engaged with the right hand one of the two holes to maintain the parts in such position, while if the parts are swung to their right hand position and the gear W engaged directly with the pinion Q on the engine-shaft the latch-pin will be engaged with the left hand end of one of the two holes, to maintain the parts in this latter position. A pin or finger-piece B'' projecting vertically from the latch-pin B' through a slot in its housing furnishes a means for withdrawing the latch-pin from engagement with the holes when it is desired to shift the parts.

The tool-shaft X in the present instance has secured upon its lower end an internally threaded socket-piece C'' adapted to receive the chucks or holders for the different kinds of tools to be used with the machine. In Figs. 1 and 2 there is shown at the top of the machine the usual force-feeding device D'' whose screw engages an internally threaded nut E'' screwed into the upper end of the sleeve Y. Immediately beneath the lower end of the sleeve Y the tool shaft is enlarged, forming an annular shoulder, between which and the lower end of the sleeve Y is confined a circle of antifriction balls, which take the end-thrust of the machine under the action of the force-feeding device D'' and lessen the friction between the parts.

As will be understood from the foregoing

description, I have produced an exceedingly simple and compact engine of the character described, which is capable at the same time of developing a high speed and great power relatively to its size and weight, and have provided novel and simple means for reversing its direction of motion at will, and for quickly changing the relative speed of the tool-shaft driven by it. 70

Having thus fully described my invention, 75 I claim:

1. In a machine of the character described, the combination of a casing, a double crank shaft journaled therein, a pair of oscillating engines also mounted therein so as to oscillate on axes parallel with the crank shaft, and having their piston rods connected to the cranks of said shaft, a tool shaft mounted parallel with and out of alinement with said crank shaft, and variable speed gearing connecting the crank shaft and the tool shaft, substantially as described. 80

2. In a machine of the character described, the combination of a casing, a double crank shaft journaled therein, a pair of oscillating engines also mounted therein and having their piston rods connected to the cranks of said shaft, a tool shaft mounted parallel with and out of alinement with said crank shaft, said tool shaft being movable toward and from the crank shaft, and gears intermediate the two shafts, substantially as described. 90

3. In a machine of the character described, the combination of a casing, a shaft journaled in said casing and provided with a plurality of cranks, a plurality of oscillating engines also mounted in the casing and arranged side by side with their pistons connected to said cranks, a pinion at the outer end of the shaft, a gear mounted upon a stub shaft at the side of said pinion, a second pinion secured to said gear, a tool shaft mounted lateral of and parallel with the crank shaft, a gear on said tool shaft, and means for engaging the pinion on the crank shaft with the gear on the stub shaft or with that on the tool shaft, whereby the speed of the tool shaft may be varied. 100

4. In a machine of the character described, the combination of a casing, a double crank shaft journaled therein, a pair of oscillating engines also mounted therein, side by side with their axes of oscillation parallel to said crank shaft and having therein piston rods connected to the cranks of said shaft, a tool shaft mounted parallel with and out of alinement with the crank shaft, a train of gears intermediate the two shafts, and means for shifting the relative positions of the gears for the purpose of gearing the tool shaft more or less directly to the crank shaft, and thereby increasing or decreasing its speed relatively to that of the crank shaft, substantially as described. 115

5. In a machine of the character described, the combination of a casing, a double crank shaft journaled and inclosed therein, a pair of oscillating engines also mounted and inclosed therein and having their piston rods connected to the cranks of said shaft and having angular adjustment in respect thereto, a tool shaft mounted parallel with the crank shaft, a train of gears intermediate the two shafts, and means for shifting the relative positions of the gears for the purpose of gearing the tool shaft more or less directly to the crank shaft, and thereby increasing or decreasing its speed relatively to 15 that of the crank shaft, substantially as described.

6. In a machine of the character described, the combination of a casing, a double crank shaft journaled therein, a pair of oscillating engines also mounted therein and having their piston rods connected to the cranks of said shaft, a tool shaft mounted in movable supports parallel to the crank shaft, and a train of gears intermediate the two shafts, where- 20 by the tool shaft may be shifted from one position to another and thereby geared more or less directly to the crank shaft, and its speed relatively to that of the crank shaft correspondingly increased or decreased, sub- 25 stantially as described.

7. In a machine of the character described, the combination of a casing, a double crank shaft journaled therein, a pair of oscillating engines also mounted therein and having their piston rods connected to the cranks of said shaft, a pinion secured upon the outer end of the crank shaft, a tool shaft mounted parallel to the crank shaft in a movable support, a gear fast upon said tool shaft, a sec- 30 ond gear mounted upon the movable support of the tool shaft, and a pinion turning with said last mentioned gear and meshing with that upon the tool shaft, the movement of the tool shaft from one position to another serving to engage one or the other of the gears with the pinion upon the crank shaft and thereby gear the tool shaft either directly or indirectly to the crank shaft, sub- 35 stantially as described.

8. In a machine of the character described, the combination of a casing, a double crank shaft journaled therein, a pair of oscillating engines also mounted therein and having their piston rods connected to the cranks of said shaft, a pinion fast upon the outer end of the crank shaft, a lever fulcrumed upon the end of the casing adjacent said pinion, a tool shaft mounted parallel with the crank shaft in a bearing carried by the forward end of said lever, a gear fast upon the tool shaft, and a gear and pinion mounted upon a stub shaft carried by the rear end of said lever, said pinion meshing with the gear upon the tool shaft, whereby upon rocking 60 said lever to one position the gear upon the

tool shaft may be engaged directly with the pinion upon the crank shaft, and upon rocking it to its opposite position the gear upon the tool shaft be disengaged from the pinion on the crank shaft and the gear upon the stub shaft engaged therewith, substantially as described. 70

9. In a machine of the character described, the combination of a casing, a double crank shaft journaled therein, a pair of oscillating engines also mounted therein and having their piston rods connected to the cranks of said shaft, a pinion secured upon the outer end of the crank shaft, a lever fulcrumed upon the bottom of the casing, an arm pivoted to the top of the casing, a long sleeve or tubular bearing rigidly connecting the forward ends of said lever and arm, a tool shaft mounted in said sleeve or bearing, a gear secured to said tool shaft, and a gear 80 and pinion mounted upon a stub shaft carried by the rear end of the lever, said pinion turning with the gear and meshing with the gear upon the tool shaft, whereby upon rocking the lever and arm in one direction the gear upon the tool shaft will be engaged directly with the pinion upon the crank shaft, and upon rocking them in the opposite direction it will be disengaged there- 85 from and the gear upon the stub shaft en- 90 gaged with the pinion upon the crank shaft, 95 substantially as described.

10. In a machine of the character de- 100 scribed, an engine or motor, an engine shaft driven by the engine or motor of the machine; a tool shaft mounted parallel with the engine shaft in a movable support, and a train of speed reducing gears intermediate the two shafts, whereby the movable support of the tool shaft permits it to be 105 shifted relatively to the engine shaft and geared directly or indirectly thereto, for the purpose of varying its speed relatively to that of the engine shaft, substantially as de- 110 scribed.

11. In a machine of the character de- 115 scribed, an engine or motor, an engine shaft driven by the engine or motor of the machine, a tool shaft mounted parallel with the engine shaft in a movable support, a train of speed reducing gears intermediate the two shafts, the movable support of the tool shaft permitting it to be shifted so as to gear it directly or indirectly with the engine shaft, and a latch or locking device 120 cooperating with the movable support of the tool shaft for holding it in its opposite shift- 125 ed positions, substantially as described.

12. In a machine of the character de- 130 scribed, the combination of an engine or motor, an engine shaft driven by the engine or motor of the machine, a pinion fast upon said shaft, a tool shaft mounted in a bearing carried by one end of a rocking lever, a gear fast upon said shaft, and a gear

and pinion mounted upon a stub shaft carried by the opposite end of said lever, said pinion turning with said gear and meshing with the gear upon the tool shaft, whereby upon rocking said lever in one direction the gear upon the tool shaft may be engaged directly with the pinion on the engine shaft, and upon rocking it in the opposite direction it may be disengaged therefrom and the gear upon the stub shaft engaged with said pinion, substantially as described.

13. In a machine of the character described, the combination of an engine or motor, an engine shaft driven by the engine or motor of the machine, a pinion fast upon said shaft, a tool shaft mounted in a bearing carried by one end of a rocking lever, a gear fast upon said shaft and a gear and pinion mounted upon a stub shaft carried by the opposite end of said lever, said pinion turning with said gear and meshing with the gear upon the tool shaft, whereby upon rocking said lever in one direction the gear upon the tool shaft may be engaged directly with the pinion on the engine shaft, and upon rocking it in the opposite direction it may be disengaged therefrom and the gear upon the stub shaft engaged with said pinion; and a latch or locking device coöperating with said lever and tool shaft to hold them in their opposite positions, substantially as described.

14. In a machine of the character described, the combination of a casing, a double crank shaft journaled therein, a pair of oscillating engines also journaled therein and having their piston rods connected to the cranks of said shaft, a pinion fast upon the outer end of said shaft, a lever fulcrumed upon the end of the casing adjacent said pinion, a tool shaft mounted parallel with the crank shaft in a support or bearing carried by the forward end of said lever, a gear fast upon said tool shaft, a second gear and pinion mounted upon a stub shaft carried by the rear end of said lever, said pinion turning with said gear and meshing with the gear upon the tool shaft, whereby upon rocking said lever in one direction the gear upon the tool shaft may be engaged directly with the pinion on the crank shaft, and upon rocking it in the opposite direction said gear may be disengaged from said pinion and the gear upon the stub shaft engaged with said pinion, and a latch or locking device mounted upon the casing coöperating with the support for the tool shaft to hold the latter in its opposite positions.

15. In a machine of the character described, the combination of the casing A, the crank shaft B journaled therein, the oscillating engines D D' also journaled therein and having their piston rods C C' connected to the cranks of the shaft B, the pinions Q fast upon the outer end of the shaft

B, the lever T fulcrumed upon the bottom of the casing A and the arm Z pivoted to the top of said casing, the sleeve or tubular bearing Y rigidly secured at its lower end to the forward end of the lever T and at its upper end to the forward end of the arm Z, the tool shaft X journaled in said sleeve or bearing Y, the gear W fast upon said tool shaft X, and the gear R and pinion V turning together upon the stub shaft S carried by the rear end of the lever T, the pinion V meshing with the gear W upon the tool shaft, and the rocking of the lever T and arm Z in one direction serving to engage the gear W directly with the pinion Q upon the crank shaft, and the rocking of them in the opposite direction serving to disengage said gear from said pinion and engage the gear R with said pinions, substantially as described.

16. In a machine of the character described, the combination of the casing A, the crank shaft B journaled therein, the oscillating engines D and D' also journaled therein and having their piston rods C C' connected to the cranks of the shaft B, the pinion Q fast upon the outer end of the shaft B, the lever T fulcrumed upon the bottom of the casing A and the arm Z pivoted to the top of said casing, the sleeve or tubular bearing Y rigidly secured at its lower end to the forward end of the lever T and at its upper end to the forward end of the arm Z, the tool shaft X journaled in said sleeve or bearing Y, the gear W fast upon said tool shaft X, the gear R and pinion V turning together upon the stub shaft S carried by the rear end of the lever T, the pinion V meshing with the gear W upon the tool shaft, and the rocking of the lever T and arm Z in one direction serving to engage the gear W directly with the pinion Q upon the crank shaft, and the rocking of them in the opposite direction serving to disengage said gear from said pinion and engage the gear R with said pinion, and the spring latch pin B' mounted upon the casing and coöperating with the lever T to hold the latter and the parts carried by it in their opposite positions, substantially as described.

17. The combination of the crank shaft B, the oscillating engine D having the ports L L' near its opposite ends, and the adjustable yoke J containing the inlet passage for the motive fluid and provided with the ports K K' adapted to coöperate with the ports L L', whereby upon adjusting said yoke from one position to another the engine may be reversed as described.

18. The combination of the casing A, the crank shaft B, the oscillating engine D having the ports L L' near its opposite ends, the slide I, the yoke J carried by the slide I and having the inlet passage for the mo-

- 5 tive fluid and the ports K K' coöperating with the ports L L', and means for adjusting the slide I for the purpose of reversing the engine, substantially as described.
- 10 5 19. The combination of the casing A, crank shaft B, oscillating engine D having the ports L L' near its opposite ends, slide I, tubular handle G secured thereto, the hollow yoke J carried by the slide I and provided with the ports K K', and means carried by the handle G for adjusting the slide I to reverse the engine, substantially as described.
- 15 10 20. The combination of the casing A, crank shaft B, oscillating engine D having the ports L L', slide I mounted in a guide way upon the casing A, the hollow yoke J carried by the slide I and having the ports K K' coöperating with the ports L L', the 70 tubular handle G secured in the slide I, the sleeve O mounted upon the handle G and provided with the teeth a', and the fixed rack a coöperating with said teeth a' on the sleeve O, substantially as described.
- 20 15 21. The combination of the casing A, crank shaft B, oscillating engine D having the ports L L', slide I mounted in a guide way upon the casing A, the fixed rack a and the enlarged plate N at the opposite sides 75 of said guide way, and the sleeve O mounted upon the handle G and having upon the one side the teeth a', coöperating with the rack a, and upon its opposite side the teeth c coöperating with notches in the plate N, substantially as described.
- 25 20 22. The combination of the casing A, crank shaft B, oscillating engine D having the ports L L', slide I mounted in a guide way upon the casing A, the fixed rack a and the enlarged plate N at the opposite sides of said guide way, the sleeve O mounted upon the handle G and having upon the one side the teeth a', coöperating with the rack a, and upon its opposite side the teeth c co- 80 operating with notches in the plate N, the collar e fast upon the handle G, and the coiled spring d surrounding the handle G within the sleeve O, substantially as described.
- 30 25 23. The combination of the pair of oscillating engines D D' provided with the ports L L' upon their adjacent sides and near their opposite ends, and the adjustable yoke J intermediate said engines, containing 85 the inlet passage for the motive fluid and provided with the ports K K' coöperating with the ports L L' of both engines, whereby the direction of motion of the engines may be reversed by adjusting the yoke J, substantially as described.
- 35 30 24. The combination of the casing A, double crank shaft B, pair of oscillating engines D D' having the ports L L' upon their adjacent sides near their opposite ends, the 90 slide I mounted in a guideway upon the cas-
- ing A, the hollow yoke J carried by the slide I and having the ports K K' adapted to coöperate with the ports L L' of both engines, and means for adjusting the slide I in its guide way for the purpose of reversing the direction of motion of the engines, substantially as described.
- 40 35 25. In a machine of the character described, the combination of a casing, a crank shaft journaled therein, an engine also mounted therein and having its piston connected to the crank of said shaft, a tool shaft, a movable bearing in which said tool shaft is journaled, and a force feeding device carried by said movable bearing whereby it is maintained in the same relative relation to the tool shaft when the bearing for the latter is moved, substantially as described.
- 45 40 26. In a machine of the character described, the combination of a casing, a double crank shaft journaled in the sides of said casing, a pair of oscillating engines mounted side by side in said casing to oscillate in parallel planes and upon an axis parallel 95 with the crank shaft, said engines having their piston rods connected to the cranks of said shaft, and a tool shaft mounted parallel with and out of alinement with said crank shaft, and gearing connecting the crank shaft and the tool shaft.
- 50 45 27. In a machine of the character described, the combination of a driving shaft, an engine operatively connected therewith, a tool shaft arranged parallel with the driving shaft, and a train of speed reducing gears intermediate said shafts, said tool shaft having an angular adjustment with respect to the driving shaft for more or less directly gearing the latter shaft to the tool 100 shaft; substantially as described.
- 55 50 28. In a machine of the character described, the combination of a driving shaft, an engine operatively connected therewith, a tool shaft arranged parallel with the driving shaft, and a train of speed reducing gears intermediate said shaft, said tool shaft having an angular adjustment with respect to the driving shaft and on an axis eccentric thereto, whereby the driving shaft may be geared more or less directly to the tool 105 shaft; substantially as described.
- 60 55 29. In a machine of the character described, the combination of a driving shaft, an engine operatively connected therewith, a tool shaft arranged parallel with the driving shaft, a train of speed reducing gears intermediate said shafts, said tool shaft having an angular adjustment with respect to the driving shaft for more or less directly 110 gearing the latter shaft to the tool shaft, and means for holding the tool shaft in its different adjusted positions; substantially as described.
- 65 60 30. In a machine of the character described, 115

- the combination, with the rotary engine shaft driven by an engine or motor of the machine and with the engine frame or casing, of a tool shaft, a movable support for 5 the tool shaft journaled on said casing on an axis eccentric to the engine shaft, and a train of speed reducing gears intermediate the two shafts whereby the movable support of the tool shaft permits the latter 10 to be shifted or adjusted angularly with respect to the engine shaft and geared directly or indirectly thereto for the purpose of varying its speed relatively to that of the engine shaft; substantially as described.
- 15 31. In a machine of the character described, the combination, with the rotary engine shaft driven by an engine or motor of the machine and with the engine frame or casing, of a tool shaft, a movable support 20 for the tool shaft journaled on said casing on an axis eccentric to the engine shaft, a gear on said tool shaft, a pinion on the engine shaft and gearing intermediate said pinion and gear, whereby when the movable 25 support is in one position the entire train of gearing is employed and when in another position the said intermediate gearing is eliminated as to operation and the said tool shaft gear operated directly by said pinion; 30 substantially as described.
32. In a machine of the character described, the combination of a casing, a shaft journaled therein, an engine arranged within the casing and operatively connected with 35 the shaft for driving it, a tool shaft support arranged extraneous of the casing and parallel with the shaft and having angular adjustment in respect thereto, a tool shaft mounted in said support, and gearing between 40 said shafts; substantially as described.
33. In a machine of the character described, the combination of a casing, a shaft journaled therein, an engine arranged within the casing and operatively connected with 45 the shaft for driving it, a tool shaft support arranged extraneous of the casing and parallel with the shaft, a tool shaft mounted in said support, a pinion on said shaft, a gear mounted on a stub shaft or stud on said 50 support, a pinion secured to said gear, and a gear secured on said tool shaft, and arranged to mesh with said last mentioned pinion; substantially as described.
34. In a machine of the character described, the combination of a casing, a shaft journaled therein, an engine arranged within the casing and operatively connected with the shaft for driving it, a support arranged extraneous to said casing and mounted thereon, said support being parallel with the 55 shaft and having a longitudinal bore, a tool shaft received by said bore, and gearing between said shafts, the gearing of the tool shaft being intermediate the length of the latter; substantially as described.
35. The combination, with a driven shaft, of an oscillating engine operatively connected therewith and having at opposite ends inlet ports or passages for the motive fluid, and a motive fluid conduit for supplying the motive fluid and adjustable with relation to 70 said ports; substantially as described.
36. The combination, with the engine casing and the driven shaft journaled therein, of an oscillating engine operatively connected therewith and having at opposite ends inlet ports or passages for the motive fluid, a motive fluid conduit for supplying the motive fluid and adjustable with relation to 75 said ports, and a slide supporting the conduit and adjustable upon the side of the casing; substantially as described.
37. The combination, with a driven shaft, of a pair of oscillating engines operatively connected therewith and arranged on the same side thereof, and an adjustable motive fluid conduit or chest common to both engines; substantially as described.
38. In a machine of the character described, the combination of a driving shaft, an engine operatively connected therewith, a tool shaft arranged parallel with the driving shaft, and having an angular adjustment with relation thereto, a movable or adjustable support for said tool shaft, a force feeding device carried by said support, and driving connections between said shafts; 90 substantially as described.
39. In a machine of the character described, the combination of a driving shaft, an engine operatively connected therewith, a tool shaft arranged parallel with the driving shaft, and having an angular adjustment with relation thereto, a movable support for said tool shaft, a train of speed reducing gears intermediate the two shafts whereby the movable support of the tool shaft permits the latter to be shifted angularly with respect to the engine shaft and to 95 be geared directly or indirectly thereto, and a force feeding device carried by said support, substantially as described.
40. In a machine of the character described, the combination of a driving shaft, an engine operatively connected therewith, a tool shaft arranged parallel with the driving shaft, and having an angular adjustment with relation thereto, a movable or adjustable support having a tubular portion 115 receiving the tool shaft, a train of speed reducing gears intermediate the two shafts, and a force feeding device carried by said tubular portion of the support; substantially as described.
41. In a machine of the character described, the combination of a driving shaft, an engine operatively connected therewith, a tool shaft arranged parallel with the driving shaft, and variable speed gearing con- 120 125 130

necting the driving shaft and the tool shaft; substantially as described.

42. In a machine of the character described, the combination of a driving shaft, 5 an engine operatively connected therewith, a tool shaft, a train of gears intermediate the two shafts, and means for shifting the relative positions of the gears for the purpose of gearing the tool shaft more or less directly 10 to the crank shaft and thereby increasing or decreasing its speed relatively to that of the crank shaft; substantially as described.

43. In a machine of the character described, the combination of a driving shaft, 15 an engine operatively connected therewith, a tool shaft, a train of gears intermediate the two shafts, means for shifting the relative positions of the gears for the purpose of gearing the tool shaft more or less directly 20 to the crank shaft and thereby increasing or decreasing its speed relatively to that of the crank shaft, and means for holding the gears in one relative position or the other; substantially as described.

44. In a machine of the character described, the combination, with a driven shaft, of an engine operatively connected therewith and having a cylinder provided with inlet ports and a motive fluid conduit 30 for supplying the motive fluid and adjustable with relation to said ports for reversing the direction of rotation of the engine; substantially as described.

45. In a machine of the character described, the combination, with the engine casing and the driven shaft journaled therein, of an engine arranged within the casing and operatively connected with said shaft, 40 said engine having inlet ports for the motive fluid, a motive fluid conduit for supplying the fluid to said ports, and a support operatively connected with said conduit and adjustable upon the casing to adjust the conduit with relation to said ports and thereby 45 reverse the direction of rotation of the engine; substantially as described.

46. In a machine of the character described, the combination, with a driven shaft, a pair of engines operatively connected therewith, and a motive fluid conduit 50 common to both engines and adjustable to

reverse the direction of rotation of the engines; substantially as described.

47. In a machine of the character described, the combination, with a casing and 55 a driven shaft journaled therein, of a pair of engines arranged within the casing and operatively connected with said shaft, and a motive fluid conduit common to both engines and supported by the casing, said conduit 60 being adjustable upon the casing to reverse the direction of rotation of the engines; substantially as described.

48. In a machine of the character described, the combination, with a driven 65 shaft, of an engine operatively connected therewith, a hollow handle for supplying the motive fluid connected with the engine for moving and steadyng the engine, and a hollow reversing yoke connected with said 70 hollow handle coöperating with the engine ports and under the control of said handle; substantially as described.

49. In a machine of the character described, the combination, with a driven 75 shaft, of an engine operatively connected therewith, a hollow grasping handle for supplying the motive fluid connected with the engine, for moving and steadyng the engine, a hollow reversing yoke connected with 80 said hollow handle coöperating with the engine ports, and means connected with the handle for operating said yoke; substantially as described.

50. In a machine of the character described, the combination, with a driven shaft, of an engine operatively connected therewith, a hollow grasping handle for supplying the motive fluid connected with the engine for moving and steadyng the engine, 90 a hollow reversing yoke connected with said hollow handle coöperating with the engine ports, and a rotatable member carried by said handle and operatively connected with said yoke for adjusting the relative position 95 thereof to reverse the direction of rotation of the engine; substantially as described.
